UNITED STATES PATENT OFFICE.

FREDERICK KUKKUCK, OF ST. LOUIS, MISSOURI, ASSIGNOR OF ONE-HALF
TO HENRY ARND, OF SAME PLACE.

TRUNK-COVER.

SPECIFICATION forming part of Letters Patent No. 268,694, dated December 5, 1882.

Application filed February 17, 1882. (No model.)

To all whom it may concern:

Be it known that I, FREDERICK KUKKUCK, of St. Louis, in the State of Missouri, have invented an Improved Trunk-Top, of which 5 the following is a specification, reference being had to the accompanying drawings.

Ordinarily the tops of trunks and analogous articles, when made of wood, consist of two or more barrel-staves, jointed to each other 10 longitudinally and made to assume the ordinary "barrel-stave" shape. Trunk-tops have also been made of veneer, but not of the barrel-stave shape, so far as I am aware, such veneer tops having merely been curved laterally—as, for example, in United States Reissue Patent of J. K. Mayo, No. 3,090, dated August 18, 1868.

My invention consists of a trunk-top formed of veneer or thin sheets of wood of the barrel-stave shape—that is to say, having the greatest arc or swell in central cross-section, the cross-sections from either side of the center being arcs of diminished height, so that the end portions of the cover have a like 25 smaller arc or curvature, the central part or swell being the largest curvature.

In the accompanying drawings, illustrating my invention, Figure 1 is a perspective view of my improved trunk-top. Fig. 2 is a plan view of the same, having portions thereof broken away to show the direction of the grain of the wood of the respective layers. Fig. 3 is a longitudinal sectional elevation on the line 30 xx . Fig. 4 is a transverse section on the line yy , through the swell of the top; and Fig. 5 is an end view to show the more diminished swell or arc.

Referring to the letters upon the drawings, A represents the lower veneer; B, the center 40 veneer; C, the top veneer. Each of said veneers (thin sheets of wood) is of the required size to suit the entire surface or dimensions of the top. The said veneers are placed one over the other, the center veneer, however, having 45 its grain running transversely, while the respective lower and upper veneers have their grain or fibers in a longitudinal direction, as indicated. The said veneers are jointed to-

gether, and by referring to the drawings it will be seen that the greatest arc (swell) of the veneering is on the transverse line yy . (See Figs. 2 and 4.) The shape, when taken on line xx longitudinally through the top, is the arc as shown in Fig. 3. Thus when taken either in cross-section or longitudinally the shape of the top is such as to possess a higher central portion, which tapers to lesser arcs to the ends. (See Figs. 1, 3, and 5.) In thus giving the veneer top the said barrel-stave shape the central portion or swell must not be strained, 50 made thinner, or weakened, but must possess much stiffness and strength, which is a great desideratum, and the entire cover will thus be light, cheap, and durable.

While such tops might be made by hand of 55 thin sheets of wood formed into shape by scooping or dishing out blocks of wood, this method of course would be too expensive for commercial purposes. Each blank must measure considerably less transversely in the arc 60 of the circle described by its ends than it measures transversely in the arc of the circle described by a cross-section through its center. Therefore some practicable method must be employed for reducing the amount of material in the sheet at its ends as compared 65 with the amount in its center without at the same time either thickening the ends or thinning the center. The best way now known to me to make the blanks from sheets to be 70 united to form the top is that set forth fully and claimed in the joint United States Patent of myself and Henry Arnd, No. 262,956, dated 75 the 22d day of August, 1882, wherein the veneer sheets are described as first gored at their 80 ends and then properly bent and united at the edges of the gores, and one to another on their 85 faces.

It will of course be practicable, without departing from the substance of my invention, 90 to make the extreme ends of my top nearly or perhaps quite straight, and to cut away or curve the sides at the edges, the main thing being to form a combined longitudinal and transverse curved or barrel-stave top of 95 veneers or thin sheets of wood.

Having thus described my invention, what I claim as new, and desire to secure by Letters Patent, is—

As a new article of manufacture, a trunk-top composed of crossing layers of veneer, first gored at their ends, and then bent and united at the edges of the gores and one to another, so as to have the greatest arc or swell

in cross-section through the center of the cover and arcs of diminished height from the center to the extreme ends, substantially as and for the purpose set forth.

FREDERICK KUKKUCK.
